UNITED STATES PATENT OFFICE.

JOHN ASHTON GREENE, OF BROOKLYN, NEW YORK.

DESIGN FOR A BELT-STUD TOOL.

SPECIFICATION forming part of Design No. 17,306, dated May 3, 1887.

Application filed March 31, 1887. Serial No. 233,214. Term of patent 14 years.

To all whom it may concern:

Be it known that I, JOHN ASHTON GREENE, a citizen of the United States, residing in Brooklyn, in the county of Kings and State of New York, have invented and produced a new and original Design for a Belt-Stud Tool, of which the following is a specification.

The nature of my design is fully represented in the accompanying drawing, to which reference is made.

The leading feature of my design consists in the arm of the tool, which has a slightly-curved form with an extremity tapering in both directions nearly to a point.

15 A and B are the arms of the tool. The arm A is formed on a reversed curve, and its extremity is turned toward the arm B. The arm B is elongated. Its middle portion is formed on a reversed curve and rounded on its sides.

20 On the arm B, at a point about opposite the end of the arm A, there are shoulders *a*, which

project from opposite edges of the arm B, and the end of the said arm B, from the shoulders *a* to the point thereof, is of a rectangular form in cross-section, and is diminished in width and thickness from the shoulders *a* to the point D, the end of the arm B thus being made of a tapering form from the shoulders *a* to the extremity thereof.

25 I claim—

The design for a belt-stud tool herein shown and described, the same consisting in a curved arm, A, having its ends turned inward toward the arm B, and an arm, B, formed on a reversed curve in its middle portion with shoulders *a*, and an end of rectangular form in cross-section tapering from the shoulders toward the point D.

30 JOHN ASHTON GREENE.
